IMPACT WRENCH

John P. Newman, Los Angeles, Calif.

Application July 19, 1948, Serial No. 39,383

7 Claims. (Cl. 192—30.5)

1

This invention relates to a new and improved form of impact wrench.

A particular object of the invention is to provide a power driven impact wrench having means for adjustment of the magnitude of the blows or impacts delivered by the wrench.

Another object is to provide improved structure for alternately connecting and disconnecting the driven member from the power driven drive shaft.

Another object is to provide an impact wrench having working parts which are capable of economical manufacture in quantity and which may be readily disassembled for inspection, repair or replacement.

Further and more detailed objects and advantages will appear hereinafter.

In the drawings:

Figure 1 is a side elevation partly in section showing a preferred embodiment of my invention.

Figure 2 is a front elevation thereof.

Figure 3 is an axial sectional view partly broken away of that portion of the device indicated by the circle 3—3 in Figure 1.

Figure 4 is a sectional view of a modified form of the device illustrated in Figure 3.

Figure 5 is a sectional elevation taken substantially on the lines 5—5 as shown in Figure 3.

Figure 6 is a sectional view taken substantially on the lines 6—6 as shown in Figure 4.

Figure 7 is an end view of the adjusting wedge used in connection with my invention.

Figure 8 is a side elevation of the adjusting wedge.

Figure 9 is a side elevation of the cam member utilized in connection with that form of my invention shown in Figures 1 and 3.

Figure 10 is a rear elevation thereof.

Figure 11 is a front elevation of the cam member.

Figure 12 is a side elevation partly broken away of the driver member employed in that form of my invention shown in Figures 1 and 3.

Figure 13 is a front end elevation thereof.

Referring to the drawings, the impact wrench embodying my invention may be provided with an electric motor 10 suitably mounted within a housing 11. A downwardly extending handle portion 12 on the housing 11 is proportioned to be received within the palm of the hand of the user, and a trigger element 13 pivotally mounted on the handle portion is adapted to operate a control switch (not shown) for regulating the operation of the electric motor 10. Electrical current for the motor may be supplied through

2

the cable 14. A switch lever 15 may also be mounted on the handle 12 for reversing the direction of the motor 10 when desired. It is recognized that an air driven motor may be substituted for the electric motor if desired, since the type of power means employed for turning the drive shaft does not constitute an important part of my invention.

Reduction gearing may be provided for driving the drive shaft 16 from the motor shaft 17, and as shown in the drawings this gearing may include the small pinion gear 18 on the motor shaft driving the larger gear 19 on the countershaft 20. A pinion 21 also fixed on the countershaft 20 engages the larger driven gear 22 which is fixed to the drive shaft 16 by any convenient means such as, for example, the key 23. The housing 11 provides suitable bearings for the motor shaft 17 and for the rearward end of the drive shaft 16.

A cylindrical housing extension or shell 24 is telescopically received over the forward projection 25 of the housing 11 and is releasably connected thereto by means of the spring urged detent 26 which is received in a lateral opening 27 in the shell 24. The forward projecting end of the shell 24 is connected by any suitable means to the bearing sleeve 28. A drive shaft 16 extends axially through the shell 24 and its outer end 29 extends into the bearing sleeve 28. A resilient drive sleeve 30 encircles the drive shaft 16 for a portion of its length and is connected at its rearward end in driving relationship with the drive shaft 16 by means of the pin connection 31. The forward end of the sleeve 30 is connected by pins 32 to the hammer member 33 which is rotatably mounted within the shell 24. The sleeve member 30 is preferably constructed of rubber or of rubberlike material so that the forward end of the sleeve and the hammer member 33 may be driven by the shaft 16 but be capable of relative angular movement with respect thereto.

The hammer member 33 is provided with a transverse slot 34 at its forward end and a shuttle or locking dog 35 is adapted to reciprocate within this slot (see Figure 5). This locking dog is provided with a central elongated opening 36 for reception of the shaft 16, and the opening extends in the direction of the slot 34 so that the shuttle or locking dog 35 may move radially with respect to the shaft 16. A compression spring 37 mounted in a cavity 38 and resting on a shoulder 39 within the locking dog 35 urges a contact shoe 40 into engagement with the shaft 16 so

that the locking dog 35 is normally biased to move in a radial direction. The locking dog 35 is provided on its forward side with a cylindrical bore 41. The cylindrical portion 42 of the cam member 43 is positioned eccentrically with respect to the bore 44 which receives the forward end of the drive shaft 16. This eccentric 42 is received within the bore 41 in the locking dog 35.

The external cylindrical surface 45 of the cam member 43 is rotatably received within the cylindrical bore 46 of the driver member 47. The driver member 47 is in turn rotatably mounted within the bearing sleeve 28. As shown clearly in Figures 12 and 13 the driver member 47 is provided with circumferentially spaced projections 48 and 49 on which are provided driving jaw surfaces 50, 51, 52 and 53. The forward end of the driver member 47 projects from the bearing sleeve 28 and is provided with a noncircular portion 54. This noncircular portion 54 ordinarily is formed as a square. A conventional socket member 55 is provided with a square opening 56 for reception of the noncircular projection 54 and is also provided with the usual socket 57 for reception of a nut or bolt head. A retaining spring 58 may be mounted in a groove on the forward end of the driver 47 for frictional engagement with the socket member to retain the same in position.

The projecting end of the driver 47 is axially threaded as shown at 59 to receive a set screw 60. A central protrusion 61 on the set screw 60 contacts the end 62 of the adjusting wedge member 63. As shown in Figures 7 and 8, this adjusting wedge has a nose portion 64 constituting a cylindrical element cut away by a plane 65 on its lower side and having laterally extending ears 66 at its forward end. The ears 66 are received within the slot 67 formed in the forward end of the cam member 43 (see Figures 9 and 10). The set screw 60 may be adjusted axially so that the adjusting wedge member 63 has greater or less clearance along the plane 65 with the complementary inclined plane surface 68 formed near the forward end of the drive shaft 16. The set screw 60 can be threaded axially to take up all clearance between the surfaces 65 and 68 or it can be retracted to permit clearance to develop between these plane surfaces. It will be noted that the adjusting screw is readily accessible through the threaded opening 59 for adjustment of the clearance between the surfaces 65 and 68 without disassembling the parts of the impact wrench.

In operation the drive shaft 16 is turned by the motor 10 and reduction gearing. So long as no resistance to rotation is imposed by the socket member 55 the drive shaft 16, hammer member 33, locking dog 35, cam member 43 and driver 47 rotate as a unit with respect to the shell 24 and bearing sleeve 28. When resistance to rotation of the socket member 55 is encountered the driver 47 slows down relative to the drive shaft 16. The shuttle or locking dog 35 moves radially outwardly under action of the spring 37. As soon as its end surface 69 moves angularly out of engagement with the arcuate surface 70 defining the inner boundary of the lug 49 on the driver 47, the locking dog 35 is then in the position shown in phantom lines in Figure 13. Since the driver 47 is rotating slower than the hammer member 33 and locking dog 35, the locking dog moves angularly relative to the driver 47 until it contacts the jaw face 50 on the lug 48. This results in an impact which is transmitted to the driver 47 and socket member 55. The hammer member 33 changes its rate of angular rotation very rapidly,

and its rotating inertia therefore is available to produce the required shock or impact.

When the shuttle or locking dog 35 engages the jaw face 50 it acts as a key to connect the hammer member 33 solidly with the driver 47. Since the hammer member is driven by the resilient sleeve 30 it is enabled to slow down or stop momentarily while the rotation of the drive shaft 16 continues, the relative rotation being absorbed by the resilience of the rubber-like sleeve 30. Continued rotation of the drive shaft 16 acts to turn the cam member 43 relative to the locking dog 35, and the eccentric 42 then engages the cylindrical surface 41 within the locking dog to 10 retract it toward the axis of the drive shaft 16. As soon as the locking dog is retracted toward a central position it ceases to engage the jaw face 50 and takes its position with its outer end 69 in engagement with the arcuate surface 71 within the lug 48. Resistance to rotation imposed by the socket member 55 will continue to cause relative turning motion between the driver 47 and the drive shaft 16 with the result that the spring 37 will shift the locking dog 35 within its groove 34 in the hammer member 33 and cause it to strike a blow against the jaw face 53 on the lug 49. If the socket member 55 is engaged in tightening a nut on a bolt the effect is 20 to apply two separate impacts per revolution of the drive shaft 16. When the nut reaches its final tightened position the socket member 55 and driver 47 cease to rotate at all with the result that the hammer member 33 comes to a stop and accelerates rapidly twice during each revolution of the drive shaft 16. If it is desired to 30 remove a tightened nut from a bolt, or if it is desired to tighten a nut having left-hand threads, the direction of the motor 10 is reversed by means of the switch 15 and in such cases the jaw faces 52 and 51 on the driver 47 become operative. The action of the shuttle or locking dog 35 and cam member 43 is substantially the same, however.

The magnitude of the individual impacts 40 transmitted to the driver 47 may be varied by adjusting the screw 60. This serves to adjust the amount of clearance provided between the surface 65 on the wedge member 63 and the surface 68 on the end of the drive shaft 16. In effect this produces a lost motion connection between the drive shaft 16 and the cam member 43, and this in turn changes the extent of relative angular movement permitted between the drive shaft 16 and the hammer member 33. The 50 rubber-like sleeve 30 is therefore wound up to a greater angular extent when the wedge member 63 is retracted than when it is advanced. The rearward end of the rubber-like sleeve member 30 turns at a uniform angular rate with the 60 drive shaft 16 since it is connected to it by drive pin 31. The forward end, however, which is connected to the hammer member 33 turns non-uniformly and the extent of angular movement with respect to the shaft depends on the point 65 in the operating cycle at which the cam 43 moves the locking dog 35 to release the driving connection between the hammer member 33 and the driver member 47. Thus, by turning the set screw to increase the clearance between the surfaces 65 and 68, a heavier impact is transmitted to the driver 47. Conversely adjustment of the screw 60 in a direction to reduce the amount of clearance between the surfaces 65 and 68 reduces the magnitude of the individual impacts. This is a 70 highly desirable feature since it enables the im-

pact wrench assembly to be used over a wide range of sizes of bolts and nuts.

Should it be necessary or desirable to inspect the operating parts of the impact wrench assembly, the spring urged detent 26 is manually depressed to permit the shell 24 and associated parts contained therein to be moved axially away from the motor and gear housing 11. The drive pin 31 remains in the drive shaft 16 and the sleeve 30 with its driving slots 30a for the pin 31 remains with the shell 24.

In the modified form of my invention shown in Figures 4 and 6, the radially movable shuttle 35 is replaced by an axially movable clutching dog 100. This clutching dog 100 is mounted in a radial slot 101 formed in the end face of the hammer member 33a. The cam member 43 is replaced by the cam member 102 and the driver member 47a is provided with jaw faces 104. A coil spring 105 encircles a portion of the drive shaft 16a. This spring engages the central boss portion 106 of the clutching dog 100 at one end and engages a collar 107 at the other end. The collar 107 is fixed on the shaft 16a. The resilient sleeve 30a may be substantially identical to the sleeve 30 described in connection with the other figures. The shell 24a and bearing sleeve 28a likewise may be identical to those previously described.

The cam member 102 is rotatably mounted within the driver member 47a and receives the adjusting wedge 63a in a manner similar to that previously described. The rearward end face 108 of the cam member 102 comprises a plane radial surface which is interrupted for a portion of its periphery by a raised eminence or cam nose 109. This raised eminence is symmetrical in that it slopes equally on both sides to a central high point. A counterbore 110 is provided in the cam member 102 to receive the forward end of the boss 103 of the clutching dog when the dog is in its forward operative position. A rounded surface 111 is provided on the clutching dog which is adapted to ride on the cam surface 109 and on the radial surface 108. Relative angular movement between the hammer member 33a and the cam member 102 causes the clutching dog 100 to move axially along the drive shaft 16a. The clutching dog 100 is moved to the left as shown in Figure 4 under action of the compression spring 105 and is moved to the right by the engagement of the cam surface 109 with the follower surface 111. In operation the drive shaft 16a, sleeve 30a, hammer member 33a, cam member 102 and driver 47a rotate as a unit so long as no resistance to rotation is imposed upon the noncircular projection 54a. When such resistance is encountered the driver 47a slows down or stops. The clutching dog 100 is carried around with the hammer member 33a and the follower 111 returns down the slope of the cam surface 109 and onto the radial surface 108. This brings the radially extending ear 112 of the clutching dog 100 into engagement with one of the jaw faces 104. An impact results on the driver 47a. The hammer member 33a is then solidly connected with the driver 47a through the sides of the slot 101, clutching dog 100 and jaw face 104. The hammer member 33a remains at rest or rotates at a slower speed than the shaft 16a while the cam member 102 rotates to bring the raised eminence or nose 109 into contact with the follower portion 111 and thus move the clutching dog back into the bottom of the slot 101 and out of engagement with the jaw face

104. The end of the drive shaft 16a is slanted on an inclined plane surface 68a for engagement with the corresponding plane surface 65a on the adjusting wedge 63a. Movement of the adjusting screw 60a has the effect of varying the magnitude of the individual impacts delivered to the driver 47 in the same manner as described above.

Having fully described my invention, it is to be understood that I do not wish to be limited to the details herein set forth, but my invention is of the full scope of the appended claims.

I claim:

1. In an impact wrench, the combination of: a drive shaft; a driver member mounted coaxially of the drive shaft; power means for rotating the drive shaft; a hammer member rotatably mounted coaxially of the drive shaft; a resilient driving member adapted to rotate the hammer member and driven from the drive shaft; a movable clutch element slidably mounted with respect to the hammer member and constrained to rotate therewith; the drive member being provided with a jaw face; a cam member; means including relatively adjustable elements forming an angular lost motion connection whereby the cam member may be driven from the drive shaft; resilient means acting to move the clutch element into engagement with the jaw face; and cooperating parts on the cam member and clutch element for moving the latter in a direction in opposition to said resilient means.

2. In an impact wrench, the combination of: a drive shaft; a driver member mounted coaxially of the drive shaft; power means for rotating the drive shaft; a hammer member rotatably mounted coaxially of the drive shaft; a rubber-like sleeve member adapted to rotate the hammer member and driven from the drive shaft; a movable clutch element slidably mounted with respect to the hammer member and constrained to rotate therewith; the driver member being provided with a jaw face; a cam member; means including relatively adjustable elements forming an angular lost motion connection whereby the cam member may be driven from the drive shaft; resilient means acting to move the clutch element into engagement with the jaw face; and cooperating parts on the cam member and clutch element for moving the latter in a direction in opposition to said resilient means.

3. In an impact wrench, the combination of: a drive shaft; a driver member mounted coaxially of the drive shaft and provided with a non-circular projecting end; a hammer member rotatably mounted coaxially of the drive shaft; a resilient driving member adapted to rotate the hammer member and driven from the drive shaft; a movable clutch element slidably mounted with respect to the hammer member and constrained to rotate therewith; the driver member being provided with a jaw face, a cam member; means including relatively adjustable elements forming an angular lost motion connection whereby the cam member may be driven from the drive shaft, one of said elements being accessible through the projecting end of the driver member; resilient means acting to move the clutch element into engagement with the jaw face; and means on the cam member for moving the clutch element in a direction in opposition to said resilient means.

4. In an impact wrench, the combination of: a drive shaft; a driver member mounted coaxially of the drive shaft and provided with a non-

circular projecting end; a hammer member rotatably mounted coaxially of the drive shaft and provided with a radial slot; a resilient driving member adapted to rotate the hammer member and driven from the drive shaft; a movable clutch element slidably mounted in the hammer member slot; the driver member being provided with a jaw face; a cam member; means including relatively adjustable elements forming an angular lost motion connection whereby the cam member may be driven from the drive shaft, one of said elements being accessible through the projecting end of the driver member; resilient means acting to move the clutch element into engagement with the jaw face; and means on the cam member for moving the clutch element in a direction in opposition to said resilient means.

5. In an impact wrench, the combination of: a drive shaft having a plane surface inclined with respect to the shaft axis; a driver member mounted coaxially of the drive shaft and provided with a noncircular projecting end; a hammer member rotatably mounted coaxially of the drive shaft; a resilient driving member adapted to rotate the hammer member and driven from the drive shaft; a movable clutch element slidably mounted with respect to the hammer member and constrained to rotate therewith; the driver member being provided with a jaw face; a cam member; means including an adjustable wedge element adapted to cooperate with the said plane end surface on the shaft to form an angular lost motion connection whereby the cam member may be driven from the drive shaft; resilient means acting to move the clutch element into engagement with the jaw face; and means on the cam member for moving the clutch element in a direction in opposition to said resilient means.

6. In an impact wrench, the combination of: a power driven shaft; a driver member and a hammer member each rotatably mounted coax-

ially of the shaft; a resilient driving member encircling the shaft and adapted to rotate the hammer member upon rotation of the shaft; a radially movable clutch element slidably mounted with respect to the hammer member and constrained to rotate therewith; the driver member being provided with a jaw face; a cam member; means whereby the cam member may be driven from the drive shaft; resilient means acting to move the clutch element radially into engagement with the jaw face; and cooperating parts on the cam member and clutch element for moving the latter away from the face in opposition to said resilient means.

15 7. In an impact wrench, the combination of: a drive shaft; a driver member mounted coaxially of the drive shaft; power means for rotating the drive shaft; a hammer member rotatably mounted coaxially of the drive shaft; a rubber-like 20 sleeve adapted to rotate the hammer member and driven from the drive shaft; a radially movable clutch element slidably mounted with respect to the hammer member and constrained to rotate therewith; the driver member being provided with a jaw face; a cam member; means whereby the cam member may be driven from the drive shaft; a spring carried on the clutch member and acting against the drive shaft to move the clutch element radially outwardly into 25 engagement with the jaw face; and an eccentric 30 on the cam member for moving the clutch element radially inwardly in opposition to said spring.
